US0D1067974S

(12) **United States Design Patent** (10) **Patent No.:** **US D1,067,974 S**
(45) **Date of Patent:** **** Mar. 25, 2025**

(54) **COLOR SWATCH**

(71) Applicant: **NSK LTD.**, Tokyo (JP)

(72) Inventors: **Takenobu Inaba**, Fujisawa (JP);
Keisuke Yokoyama, Fujisawa (JP);
Shunsuke Iwase, Fujisawa (JP)

(73) Assignee: **NSK LTD.**, Tokyo (JP)

(**) Term: **15 Years**

(21) Appl. No.: **29/851,716**

(22) Filed: **Aug. 31, 2022**

(30) **Foreign Application Priority Data**

Mar. 4, 2022 (JP) ..... 2022-004481 D

(51) **LOC (15) Cl.** **19-06**

CLAIM

The ornamental design for a color swatch as shown and described.

DESCRIPTION

The sole FIGURE is a front view of a color swatch showing our new design, the opposite side being unornamented, and the design is of no appreciable thickness.

The broken lines shown represent portions of the claimed design and form no part of the claimed design.

1 Claim, 1 Drawing Sheet
